Application March 16, 1936, Serial No. 69,172

14 Claims. (Cl. 194—19)

Our invention relates to an improvement in meters for measuring predetermined periods of time, and more particularly to coin controlled meters of this type which handle an inserted coin automatically, independent of the operator.

The objects of the invention are to provide a device of this class which will visibly measure the passing of a certain predetermined period of time; which is automatically rendered operable after the insertion of a coin of predetermined denomination, without the turning of a key or the working of any other operably connected exterior parts; which will allow the insertion of more than one coin at a time and will measure the full predetermined period of time for each coin inserted; which will allow coins of smaller denomination to pass through the device freely without following the normal route of a coin of proper denomination, and without affecting the mechanism; which will notify the inserter of a coin both audibly and visibly when the device has commenced operation; which will visibly notify an observer when the predetermined period of time has elapsed; which will visibly notify an observer when a slug or token, instead of a coin, has been inserted to operate the device; which is new, novel, practical, and of utility; and, which will be efficient in accomplishing all the purposes for which it is intended.

With these and other objects in view as will more fully appear hereinbelow, our invention consists in the construction, novel features, and combination of parts hereinafter more fully described, pointed out in the claims hereto appended, and illustrated in the accompanying four-sheet drawing, of which,

Figure 1 is a front elevation of the device showing the relative positions of the various parts just after a coin has been inserted but before the device has actually begun the measuring of time;

Figure 2 is a front elevation of the device showing the relative positions of the various parts when the device is not operating;

Figure 3 is a front elevation of the device with the coin plate and the guide plate removed, showing the relative positions of the various parts of the reset mechanism as the indicator reaches its operative position;

Figure 4 is a front elevation of the gear housing only, showing the relation of the various gears in the two separate gear trains to each other;

Figure 5 is a rear elevation of the device showing the relation of the bell and clapper to the rest of the device;

Figure 6 is a plan elevation of the two main

drive gears showing their relation to the main spring, a portion of one of the gears being cut away;

Figure 7 is a plan elevation of the ratchet wheel and pawls, and their relation to one of the intermediate gears of the primary gear train;

Figure 8 is a sectional view of the ratchet wheel and gear taken along the line 8—8 of Fig. 7, and shows the relation of these parts to the shaft and pinion with which they co-operate;

Figure 9 is a pictorial elevation showing the action of a newly inserted coin on the primary gear train trigger, as well as the relation of the previously inserted coin to the coin ejector;

Figure 10 is a view similar to Fig. 9 showing the previously inserted coin being ejected and the newly inserted coin about to be released by the moving coin pin;

Figure 11 is a similar view showing the newly inserted coin just after it has been released by the coin pin and has begun its travel toward its position of visible display; and,

Figure 12 is a front elevation of the portion of the device which prevents the reserve coin from passing into operative relation with the device until the period of time paid for by the previously inserted coin has elapsed.

Figure 13 is a side perspective view of a preferred type housing for the device.

Like characters of reference designate like parts in all the figures.

It is understood that various changes in the form, proportion, size, shape, weight, material and other details of construction, within the scope of our invention may be resorted to without departing from the spirit or broad principle of our invention and without sacrificing any of the advantages thereof; and it is also understood that the drawings are to be interpreted as being illustrative and not restrictive.

The inventive idea involved is capable of receiving a variety of mechanical expressions only one of which, for the purpose of illustration, is shown in the accompanying drawings. Any suitable housing for the device may be provided, and we do not wish to limit ourselves to any particular housing. A housing 120 (Fig. 13) having two oppositely aligned windows 121 for visible display of a signal flag 28, and a small window 122 for visible display of the last coin inserted, is preferable.

In Fig. 4 may be seen the front plate 1 of the gear train housing, the rear plate 2 being shown only in Fig. 5. These two plates are spaced apart

by spacers 3, 4, 5, 6, and 7, riveted to the front plate 1 and secured to the rear plate by nuts 8.

Still referring to Fig. 4, between the front and rear plates are rotatably mounted: a primary drive gear 9 rotatable with a shaft 10; a gear 11 rotatable with a shaft 12; a pinion 13 and a gear 14 both rotatable with a shaft 15 when it turns in one direction, gear 14 being rotatable on the shaft 15 when it turns in the opposite direction; a pinion 16 and a gear 17; both rotatable with a shaft 18; a pinion 19 and a gear 20 rotatable with a shaft 21; a pinion 22 and a gear 23 rotatable with a shaft 24; and a pinion 25 and a fan 26 rotatable with a shaft 27. The 10 shafts are all journaled in perforations in the two main plates 1 and 2. These gears constitute the primary gear train the purpose of which is to provide the power to operate mechanism to be hereinafter described, which raises a flag 20 28 (Fig. 3) and sets an indicator 29, and performs other functions.

The power is transmitted from the primary drive gear 9 to the gears and pinions in the order named. A brake arm 52 has its inner end rigidly 25 secured to a shaft 53 which is also journaled between the two main plates. The partial rotation of the shaft 53 raises the brake arm 52 and allows the fan 26 and all the gears in the primary train to start movement. The release of the 30 shaft 53 allows the brake arm 52 to drop by gravity into contact with the fan 26, thus stopping the entire primary gear train. The shaft 12 limits the downward movement of brake arm 52.

A secondary gear train, the gears of which 35 are mounted in a similar manner, operates entirely independent of the primary gear train and is composed of the following: a secondary drive gear 30 rotatable on the shaft 10; a gear 31 (Fig. 5) and a gear 32 (Fig. 4) rotatable with a shaft 33; a pinion 34 and a gear 35 rotatable with a shaft 36; a pinion 37 and a gear 38 rotatable with a shaft 39; a pinion 40 and a gear 41 rotatable with a shaft 42; a pinion 43 and an escapement wheel 44 rotatable with a shaft 45; 45 an escapement arm 46 movable with a shaft 47; and a balance wheel 48 movable with a shaft (not shown). The power is transmitted from the main gear to each of the other gears and pinions in the order named.

50 Power is provided by a main spring 49 (Fig. 6) enclosed between the two drive gears 9 and 30 by by a cylindrical housing 50 which is secured to and rotates with gear 30. The outer end of the main spring 49 is attached to the housing 50 in a suitable manner and the inner end is secured to the shaft 10. The spring 49 drives these drive gears 9 and 30 in opposite directions, the gear 9 driving the primary gear train and the gear 30 driving the secondary gear train. The secondary 55 gear train is similar to the gear train of an ordinary clock and moves the indicator 29 (Fig. 3) mounted on the shaft 33, at an average predetermined speed. The usual hair spring 51 surrounds and is attached to the balance wheel 55 shaft (not shown) and regulates the speed of the gear train, and of the indicator 29. The secondary drive gear 30 continuously operates the secondary gear train as long as the main spring 49 is kept wound.

70 The winding mechanism will now be described. One end of shaft 12 (see Fig. 5) is threaded and carries a square lug 52 which fits a similar shaped recess in the end of a key, not shown. The turning of the key rotates gear 11, pinion 13, shaft 15, and ratchet gear 123 (Fig. 7) which gear is ro-

tatable with the shaft 15 and is allowed to turn in one direction by the pawls 54 and 55 pivotally mounted on the gear 14. A spring 56 holds the pawls in contact with ratchet 123. Gear 11 is thereby allowed to rotate drive gear 9 without rotating gear 14, or any of the other gears in the primary gear train.

The propelling mechanism which we have described is one manner of providing power for driving the time indicator and the reset mechanism. Other power means may be used, and other arrangements of the gears in the gear train may be made, and we do not wish to be limited by this one disclosure.

The most important part of our invention will now be described. We refer to the reset mechanism, more clearly illustrated in Fig. 3. The drive wheel 57 rotates with shaft 18 (driven by the primary gear train) which extends through plate 1. The wheel 57 drives the eccentric link 58 one end of which is pivotally mounted in a suitable manner on the outside surface and near the rim of the wheel. The other end of link 58 is pivotally attached adjacent the inner surface of the lower end 59 of a coin holder 60, which in turn is pivotally mounted near its center on the extended end of shaft 10. The upper end 61 of coin holder 60 pivotally mounts, adjacent its inner surface, one end of a connector link 62, the other end of which is pivotally mounted 30 adjacent the inner surface and near one edge of a reset plate 63, which in turn is rotatable on an extension of shaft 33, and is spaced away from plate 1 by a spacer collar (not visible). The plate 63 and the coin holder 60 rotate in the 35 same plane, as do the links 58 and 62.

The indicator 29 is mounted on shaft 33 outside the plate 63. It is normally moved by the shaft 33, when it rotates, by the frictional engagement of two tri-pronged spring members 64 and 65 pressed lightly against each of its sides by nuts 66 and 67, adjustable on the threaded end of shaft 33. When the indicator is inoperative, however, the secondary gear train continues to rotate shaft 33 even though the indicator does not move. The lightness of the frictional contact allows this movement of the shaft.

The indicator 29 has a short integral rearwardly extending lug 68 which is adapted to contact the lower surface of an arcuate flange 69 integral with a flag bracket 70 to which is secured the time measuring signal flag 28. The bracket 70 and flag 28 pivot as one piece about a short shaft 12, one end of which is suitably secured to the front plate 1 and the other end of which is threaded to receive a nut 71, which holds the bracket in position. The bracket 70 also carries an integral forwardly extending flange 74 which is positioned to be contacted by the edge of plate 63 as it rotates, thus raising the flag 28 60 into a measuring position, as shown in Fig. 3.

A time stud 75 is threaded at one end and is adapted to be screwed into any one of a number of threaded perforations 76 located in an arc near the outer edge of plate 63. The stud 75 rotates 65 with plate 63 in the same plane as that in which the indicator 29 rotates. The stud is adapted to contact the edge of and move the indicator 29 as the plate 63 moves, thus setting the indicator with relation to the flag 28. Fig. 3 shows the plate 70 63 at its maximum of clockwise movement. The stud 75 is in the 60 minute perforation and has therefore set the indicator to measure a full 60 minute period. If it is desired to measure only a 30 minute period, the stud 75 is set in the 30 75

minute perforation, in which case the maximum clockwise movement of the plate 63 causes the stud 75 to move the indicator 28 to the 30 minute marking on the flag.

5 The reset mechanism is propelled, as previously mentioned, by the primary gear train. A starter link 71 is securely fastened on the extended end of shaft 53 by a set screw 71. Its opposite end carries a trigger pin 72, the ends of which extend 10 on either side of the link, the forwardly extending end adapted to be contacted by a coin, in a manner later to be described, and to thereby start the primary gear train by slightly raising the brake arm 52, thus allowing the brake fan 26 to 15 rotate.

20 A coin ejector 79 is secured to one end of a shaft 80 which is journaled in perforations in the two main plates 1 and 2, and whose opposite end extends beyond the rear plate 2 and carries a bell clapper 81 (see Fig. 5) adjustable on the shaft with a set screw 82. The ejector 79 (Fig. 3) is spaced away from the plate 1 by an integral spacer collar 116, which surrounds the shaft 80 between the ejector 79 and the front plate 1. A
25 coil spring 83 surrounds the spacer collar and has one of its ends anchored to a post 90 and its other end anchored to the lower end of the ejector 79. The spring tends to hold the ejector 79 in the position shown in Fig. 3. The ejector 79 has
30 a rearwardly extending lug 84 which extends almost to the wheel 57 and is adapted to be contacted by the link 58 as it is moved by the wheel. The ejector 79 also has an integral forwardly extending lug 85, the edge of which is adapted to contact a coin in a manner later to be described. The post 90 limits the counterclockwise movement of the ejector 79.

For guiding the coin to its operative position with relation to the mechanism we provide an inner guide plate 86 (Figs. 1, 2, 9, 10 and 11) to which is riveted an edge guide plate 87, which also serves as a spacer to space an outer guide plate 88 (Fig. 1 only) away from plate 86 so that a coin 114 may pass freely therebetween. Hollow spacer posts 90, 91 and 92 (Figs. 1, 2 and 3) fit suitably located perforations (not numbered) in the guide plate 86 and serve to space the plate away from the reset mechanism, allowing it free movement. The inner ends of said spacer posts 50 screw into the front plate 1. The spacer posts 90 and 91 also extend through the outer plate 88, and screws 93 and 94 (Fig. 1) screw into the ends of posts 90 and 91 to firmly hold the two plates in position. Screw 95 (Fig. 1) likewise screws down 55 tightly on plate 86. A secondary screw 96 screws into aligned threaded perforations in the plates 88, 87 and 86.

60 A plurality of spaced guide lugs 97, 98, 99, 100, 101, 102, and 103 all secured to plate 86, as well as the inner edge of plate 87, serve to guide the downward travel of a coin. The plate 86 has an inwardly flared portion 104 (Figs. 1, 2 and 12) which is adapted to be positioned adjacent a coin slot in the housing 120 which completely houses 65 the device. This flared edge 104 serves to guide a coin from the outer coin slot to the space between the two plates 86 and 88.

The plate 86 when in operative position lies in the same plane as that in which the trigger pin 78, the lug 85, and a forwardly extending coin pin 117, carried by the coin holder 60, move. To provide for free movement of pin 78 and pin 117 an arcuate through slot 105 and a smaller through cross slot 106 are provided in the plate 86. To accommodate the free movement of lug 85 an ar-

cuate notch 107 is provided in the lower edge of plate 86. The pins 78 and 117 and the lug 85 extend practically to the inner surface of plate 88 so that a coin between the two plates 86 and 88 would necessarily have to be contacted by these members. 5

Referring to Fig. 5, a gong 118 is removably secured to the rear plate 2 and encloses the clapper 81, which is adapted to normally contact the outer rim of the gong. 10

Referring to Fig. 12 we disclose one method of preventing a coin from passing into operative relation with the reset mechanism, while the time measuring mechanism is still operating due to the action of a previously inserted coin. A member 108 has an arcuate slot 109 to accommodate the movement of a pin 110 which is secured to and travels with the indicator 29. It also has a slot 111 which accommodates a pin 112 which is secured to the plate 86. The slot 111 limits the longitudinal movement of the member 108 in either direction. A spring 113 suitably mounted on the plate 86 normally holds the member 108 at its limit of movement toward the plate 87. In this position the end of member 108 is sufficiently near the plate 87 to prevent a coin from passing edge-wise between the two. As the indicator 29 nears its inoperative position (as in Fig. 2) the pin 110 contacts the end of the slot 109 and moves the member 108 away from plate 87 allowing the coin to pass downward by gravity. The member 108 is held in this position against the tension of spring 113 until the mechanism is again set in operation by the passing of another coin into operative relation with the mechanism.

Operation

In Fig. 2 the various parts are shown in their inoperative positions. A coin 114 dropped into the outer coin slot in the housing 120 is guided by flange 104 to the space between the two plates 86 and 88, whence it travels by gravity along the path defined by lugs 91, 98, 99 and 100 and the inner edge of plate 87 to the position shown by the heavy dotted lines in Fig. 1, where it contacts the trigger pin 78 and the pin 117. The weight of the coin causes it to act as a wedge between the inner edge of plate 87 and the pin 78, thus moving the pin 78 and the starter link 71. Shaft 53 (not visible in Figs. 1 and 2) is partially rotated by this movement, and raises arm 52, allowing the fan 26 to rotate, which in turn allows the primary gear train to begin operation. Shaft 18 rotates wheel 57 which in turn moves link 58. Link 58 contacts lug 84 and moves ejector 79 from the position in Fig. 2 to the position shown in Fig. 1 (dotted lines). Ejector 79 rotates shaft 80 which moves the clapper 81 (Fig. 5) from the position indicated by the letter A to the position indicated by the letter B.

The link 58 (Fig. 2) partially rotates the coin holder 60 until its arcuate edge passes the inwardly extending end of the pin 78. The pin 78 is thereby prevented from returning to its normal 65
inoperative position until the coin holder 60 returns to its normal position, as in Fig. 2, at which time the pin 78 seats in the notch in the coin holder 60 allowing the starter link 71 and the brake arm 52 to return to their normal positions, the brake arm contacting the fan 26 and stopping 70 the reset mechanism.

The rotation of the coin holder 60 moves the connector link 62, which in turn rotates plate 63; the forward portion of its arcuate edge contacts the flange 14 moving the bracket and flag from 75

their inoperative position (Fig. 2) in which position they are not visible through the windows 121 of the housing, to a position for visibly indicating time through said windows (Figs. 1 and 3).

- 6 As the plate 68 rotates, the stud 75 contacts the edge of indicator 29 moving it in a clockwise direction and into a position of visibility through said windows (121). The lug 68 passes underneath the flange 69 in a position to support the bracket and flag.

10 As the reset mechanism continues in its movement the various parts move to the positions shown in Fig. 3 which is the limit of their movement in one direction. The stud 75 has moved the indicator to the 60 minute mark on the flag. As the rotation of wheel 57 continues all the other parts return to their inoperative positions (Fig. 2) at which time the brake arm 52 contacts the fan 26 and stops the primary gear train. The bracket 78 and flag 28 are held in the position shown in Fig. 3 by the lug 68. The frictional contact of the flange 69 on lug 68 is so small that the movement of the indicator 29 is not affected.

15 The secondary gear train (which runs continuously) now moves the indicator counterclockwise across the marked face of the flag, and an observer can tell at a glance the proportion of the predetermined time which has elapsed. Needless to say, the secondary gear train is so timed as to move the indicator from the point indicated by the numeral 60 on the flag to the point indicated by the numeral 0 in a period of 60 minutes.

20 As the wheel 57 rotates (Fig. 1), the lug 64 is released from its contact with link 58 and the spring 63 returns the ejector 78 to its position shown in Fig. 2. This return movement is rapid, and causes the clapper 81 (Fig. 5) to move rapidly from its position "B" to the position "A", and to strike the gong 118 sharply, ringing the gong, and thus audibly notifying the operator that the device is in operation. The moving of the flag indicator into indicating position serves as a visible signal that the device is in operation, since in this position they are both visible through the windows 25 121 of said housing.

25 When the predetermined time has elapsed, the lug 68 passes out from under the flag 69, and allows the bracket 78 and flag 28 to drop away from the windows 121 in said housing to the position shown in Fig. 2. This movement is limited by the flange 69 contacting a spacer collar (not visible in the drawings) integral with the starter link 71, and into which the set screw 77 screws (Fig. 3). The counterclockwise movement of the indicator 29 is limited by contact with the shaft 30 72, on which the flag bracket 78 pivots.

30 Now referring more particularly to Figs. 9, 10 and 11, we will trace the travel of the coin 114 and of the previously inserted coin 115. We have already traced the movement of the coin to the position shown in Fig. 9, at which point its movement is stopped by coin pin 117 carried by the coin holder 60. At this point the edge of the coin has contacted trigger pin 78 and has moved 35 starter link 71, allowing the primary gear train to start. As the reset mechanism moves, coin pin 117 moves to the position shown in Fig. 10, the trigger 78 being held away from the edge of the coin by the arcuate edge of coin holder 60, as previously described. From this point the pin 117 moves to the position shown in Fig. 11 and the coin 114 passes by gravity downward past the pin 78 until its lower edge strikes the guide lug 103. As the pin 117 returns to its normal position (Fig. 9) it pushes the coin past the lug 103, and

the coin edge contacts the ejector lug 85. The coin is held between the lug 85 and the lug 103, as in Fig. 9, and in this position is visible through a small suitably located window in the housing (not shown). When another coin is inserted and the reset mechanism completes another cycle the ejector lug 85 moves from the position shown in Fig. 9 to the position shown in Fig. 10 and the previously inserted coin 115 is allowed to pass between the lugs 85 and 103, clearing the coin window 122 for the display of the newly inserted coin. A suitable storage means for receiving the coins may be provided in the housing. The storage means, being within the skill of an ordinary mechanic, has not been illustrated herein.

10 Obviously, the invention is susceptible of embodiment in forms other than that which is illustrated in the accompanying drawings and described herein, and applicable for uses and purposes other than as detailed, and we therefore consider as our own all such modifications and adaptations and other uses of the form of the device herein described as fairly fall within the scope of our invention.

15 Having thus described our invention, what is claimed and desired to be secured by Letters Patent, is:

20 1. In a device of the class described: a time measuring signal flag; a time indicating hand; a first actuating mechanism for moving said hand in one direction for a predetermined distance in a given predetermined period of time; automatic mechanism for moving said indicating hand in the opposite direction; a second actuating mechanism for driving said automatic mechanism; 25 brake means for normally restraining said second named actuating mechanism, adapted to release said second actuating mechanism to operate upon contact by a coin, and adapted to stop said second actuating mechanism after said automatic mechanism has returned to normal position after setting said hand; and a power unit 30 for driving both actuating mechanisms.

35 2. In a device of the class described: a time measuring signal flag; a time indicating hand; means for moving the hand a predetermined distance in one direction in a predetermined period of time; means for rendering said hand unresponsive to said moving means after said hand has traveled the predetermined distance; automatic mechanical means for moving said hand a predetermined distance in the opposite direction independent of said first mentioned moving means; means for driving said automatic hand moving means; brake means normally restraining said driving means, operable to release said driving means to operate upon contact by a coin, and to automatically stop said driving means when said automatic hand moving means has completed its function and returned to its 40 normal position; means for guiding a coin to a point of contact with said brake means; and a power unit for driving said hand moving means and said automatic mechanical means.

45 3. The combination with a housing having oppositely aligned transparent windows for the visible display of a movable time indicating hand and a signal flag, of: automatic means for moving said signal flag and said hand from inoperative non-visible positions between the walls of said housing to operative visible positions between said windows; a gear train for actuating said automatic means; means for normally restraining said gear train, being operable by the contact of a coin for releasing said gear train to operate, and for 50

stopping said gear train after said moving means has completed its function and returned to its normal position; means for guiding a coin to a point of contact with said restraining means; and a power unit for driving said gear train.

5 4. A parking meter comprising: a time indicating mechanism including a gear train for driving it in one direction; a resetting mechanism including a gear train for resetting said time indicating mechanism in the opposite direction; a power unit for driving both gear trains; and a normally set coin released brake for releasing said resetting mechanism to operate.

10 5. A device of the class described comprising: a time indicating hand; means for moving the hand a predetermined distance in one direction in a predetermined period of time; automatic mechanical means for moving said hand a predetermined distance in the opposite direction independent of said first mentioned moving means; means for driving said automatic mechanical means; and coin released brake means normally restraining said driving means.

15 6. A device of the class described comprising: a time indicating hand; means for moving the hand a predetermined distance in one direction in a predetermined period of time; means rendering said hand unresponsive to said moving means after said hand has traveled the predetermined distance; automatic mechanical means for moving said hand a predetermined distance in the opposite direction independent of said first mentioned moving means; means for driving said automatic mechanical means; and coin released brake means normally restraining said driving means.

20 7. A time indicating meter comprising: a driven time shaft; a driven reset wheel; power means for driving both; a time unit marked flag; a time indicating hand mounted on and adapted to be moved by said shaft and to indicate time in cooperation with said flag; a reset mechanism driven by said reset wheel for resetting said flag and said indicating hand, said reset mechanism adapted to start operation only when released to movement by a coin released brake; and a coin released brake for stopping said reset mechanism after it has completed its resetting function.

25 8. A parking meter comprising: a time indicating mechanism including a means for driving it in one direction; a resetting mechanism including means for resetting said time indicating mechanism in the opposite direction; a power unit for driving both means; and a normally

set coin released brake for releasing said resetting mechanism to operate.

30 9. A parking meter of the class described, comprising: a time indicating mechanism including a means for driving it in one direction; a resetting mechanism comprising a system of levers and including means for resetting said time indicating mechanism in the opposite direction; a power unit for driving both means; and a normally set coin released brake for controlling the operation of said resetting mechanism.

35 10. Organization as described in claim 9 and brake means for controlling the operation of said time indicating mechanism in said first mentioned direction.

15 11. A parking meter comprising: a time indicating mechanism including means for driving it in one direction; a normally inoperative resetting mechanism including means for resetting said time indicating mechanism in the opposite direction; a power unit for driving both means; and brake means for controlling the operation of both the time indicating mechanism and the resetting mechanism.

20 12. In a prepayment parking meter, the combination of a time-indicating mechanism including a gear train for driving said mechanism in a time-indicating direction; a resetting mechanism for moving said time-indicating mechanism in the opposite direction; power spring 30 mechanism for actuating said time-indicating mechanism and said resetting mechanism; and means responsive to a deposited coin for rendering said spring mechanism effective to actuate said resetting mechanism.

25 13. A parking meter comprising: a time indicating mechanism including a means for driving it in one direction; a resetting mechanism including means for resetting said time indicating mechanism in the opposite direction; a power 40 unit for driving both means; and coin released means for normally restraining the operation of said resetting mechanism.

30 14. A parking meter comprising: a time indicating mechanism including a gear train for driving it in one direction; a resetting mechanism including a gear train for resetting said time indicating mechanism in the opposite direction; a power unit for driving both gear trains; and coin released means for releasing 50 said resetting mechanism to operate.
